HEAT-TREATING APPARATUS

Jean F. Gschwind, Mamaroneck, N. Y., assignor
to J. O. Ross Engineering Corporation, New
York, N. Y., a corporation of New York

Application May 7, 1947, Serial No. 746,587

9 Claims. (Cl. 34—155)

1

This invention relates to heat-treating apparatus.

An object of this invention is an improved and compact apparatus for hot air treatment of webs either of the endless type or of indefinite length.

Other objects, novel features and advantages of this invention will become apparent from the following specification and accompanying drawings, wherein:

Fig. 1 is an elevation partly in section of an embodiment of the invention;

Fig. 2 is a view similar to Fig. 1 with the parts in a different position;

Fig. 3 is a fragmentary plan view of Fig. 1;

Fig. 4 is a view similar to Fig. 1 of a modification, and

Fig. 5 is a view similar to Fig. 1 of a further modification.

In each of the modifications, 10 is a housing of rectangular cross-section having vertical walls 11 and 12 of which the wall 11 is provided with a relatively small horizontal opening 13. Two horizontal rails 14 are mounted within the housing with one set of ends engaging the wall 12 and extending through the opening 13 a short distance beyond the wall 11. A cradle 15 is slidably supported by the rails 14 and a feed screw 16 is provided for moving the cradle 15 along the rails 14. The cradle 15 rotatably supports a roll 17 mounted thereon in such manner that at least one end of the roll may easily and quickly be lifted out of supported relation to said cradle. A pair of ducts 18 are provided for projecting heated air into the housing and a duct 19 is provided for withdrawing air from the housing. The withdrawn air may be heated and returned to the ducts 18 by any suitable means, not shown.

A table 20 slidably supports a second cradle 21 in which is journaled a roll 22. A feed screw 23 is provided for adjusting the cradle 21 on the table 20 toward or away from the housing 10. The roll 22 is supported by the cradle 21 in such manner that at least one end of the roll may be easily and quickly lifted out of supported relation to the cradle 21. An idler roll 29 is supported by the end of the rails 14.

To make use of the apparatus above described, an endless web 24 is trained around both rolls 17 and 22 with the roll 17 in the position shown in Fig. 1. The web is put in place by lifting one end of each roll 17 and 22 out of supported relation to its cradle and sliding the web in place, after which each such roll is returned to supported relation with its cradle. The slack on the web 24 is located between the two rolls 22

and 29. The feed screw 16 is operated to move the cradle 15 and roll 17 into the housing 10 as far as the extent of the web 24 will permit, or until the cradle reaches the wall 12. If there is any slack remaining in the web 24, the feed screw 23 is operated to move the cradle 21 and the roll 22 to the right from the position shown in Fig. 2, thereby taking up the slack and putting the web under any desired degree of tension. The roll 22 is now rotated by any suitable means (not shown) to feed the web 24 into and out of the housing 10 and through the current of hot air provided by the ducts 18. The feeding of the web 24 through the housing 10 is continued until the desired heat treatment of the web has been effected. The feed screws both adjust the cradles and lock them in adjusted position.

In Fig. 4, two friction rolls 25 are journaled near the end of the rails 14 and one of the rolls is equipped with a friction brake. Two pull rolls 26 are suitably supported somewhat to the right of the roller 25 and at least one of the rolls 25 is positively driven by any suitable means. The web 24 passes between the rolls 25 around the roll 17 and between the roll 26 with the slack being arranged intermediate the rolls 25 and 26. The web is trained around the roll 17 while it is exterior of the housing 10, after which the cradle 15 and roll 17 are fed into the housing as previously described.

The embodiment of Fig. 5 is adapted for heat-treatment of a web 24' of indeterminate length. A reel 27 supporting the web 24' is journaled in a suitable frame and is provided with a friction brake. From the reel 27, the web 24' passes around the roll 17 to the pull rolls 26 from which it passes to a take-up reel 28 provided with driving means (not shown). With the roll 17 exterior of the housing 10, the web 24' is passed around the roll 17 and between the rolls 26 to the rewinder 28. The roll 17 is then introduced into the housing as before described and the web is drawn off the reel 27 and fed through the housing 10 around the roll 17 from which it is pulled off by the rolls 26 and delivered to the rewinder 28.

In each of the embodiments herein disclosed, most of the mechanical equipment and the entire drive mechanism remain outside the housing 10 and are not exposed to high temperatures. In each instance, the threading of the web around the various rolls is accomplished exterior of the housing 10 which is provided with only one relatively small opening for introduction of the web

thereinto, thus resulting in heat saving. The threading of the web around the rolls is simple and does not require the operator to enter the housing 10 nor to thread the web by hand through the housing. The roll 17 need not travel the full length of the housing 10 so that the apparatus may accommodate short as well as long webs. The web may be maintained at any desired tension during its travel through the housing 10. This feature is especially advantageous whenever the proper treatment of the web requires a very small but controlled amount of tension.

It is of course understood that various modifications may be made in the apparatus above described, without in any way departing from the spirit of the invention as defined in the appended claims.

I claim:

1. A device of the character described comprising walls forming a closed compartment having a relatively small opening in one side wall, guide means extending substantially horizontally through said small opening into said compartment, a cradle slideable on said guide means through said small opening into and out of said compartment, a roll supported by said cradle, and means exterior of said compartment for feeding a web around said roll.

2. A device of the character described comprising walls forming a closed compartment having a relatively small opening in one side wall, guide means extending substantially horizontally through said small opening into said compartment, a cradle slideable on said guide means through said small opening into and out of said compartment, a roll supported by said cradle, means exterior of said compartment for feeding a web around said roll, and means to circulate heated air through said compartment in contact with said web.

3. A device according to claim 2 in which said web feeding means comprises a second roll supported exterior of said compartment for cooperation with the first roll.

4. A device according to claim 2 in which said web feeding means comprises a second roll adjustably supported exterior of said compartment for cooperation with the first roll.

5. A device of the character described comprising walls forming a closed compartment having a relatively small opening in one side wall, guide means extending substantially horizontally through said small opening into said compartment, a cradle slideable on said guide means through said small opening into and out of said compartment, a roll supported by said cradle, means exterior of said compartment for feeding a web around said roll, means to circulate heated air through said compartment in contact with said web, and means for locking said cradle in any given position of said compartment.

6. A device of the character described comprising walls forming a closed compartment having a relatively small opening in one side wall,

guide means extending substantially horizontally through said small opening into said compartment, a cradle slideable on said guide means through said small opening into and out of said compartment, a roll supported by said cradle, means exterior of said compartment for feeding a web around said roll, means exterior of said compartment for drawing a web through said compartment around said roll, and means for tensioning said web.

7. A device of the character described comprising walls forming a closed compartment having a relatively small opening in one side wall, guide means extending substantially horizontally through said small opening into said compartment, a cradle slideable on said guide means through said small opening into and out of said compartment, a roll supported by said cradle, and a pair of cooperating rolls exterior of said compartment for drawing a web through said compartment around said roll.

8. A device of the character described comprising walls forming a closed compartment having a relatively small opening in one side wall, guide means extending substantially horizontally through said small opening into said compartment, a cradle slideable on said guide means through said small opening into and out of said compartment, a roll supported by said cradle, means exterior of said compartment for feeding a web around said roll, means exterior of said compartment for drawing a web through said compartment around said roll, means for tensioning said web, and means to circulate heated air through said compartment in contact with said web.

9. A device of the character described comprising walls forming a closed compartment having a relatively small opening in one side wall, guide means extending substantially horizontally through said small opening into said compartment, a cradle slideable on said guide means through said small opening into and out of said compartment, a roll supported by said cradle, a pair of cooperating rolls exterior of said compartment for drawing a web through said compartment around said roll, means for tensioning said web, and means to circulate heated air through said compartment in contact with said web.
